UNITED STATES PATENT OFFICE

ERNST WILCKENS, OF BERLIN, GERMANY

SOUND-TRANSMITTING APPARATUS

Application filed June 30, 1928, Serial No. 289,601, and in Germany July 16, 1927.

The present invention relates to apparatus for emitting acoustical signals in gaseous or liquid media, and more particularly to that type in which the liquid or gaseous operating agent is supplied through a nozzle to a vibratory diaphragm for generating the necessary fluctuations in pressure by variation in volume.

It is the object of this invention to generally improve on apparatus of this type, so that the same will possess a greater efficiency and at the same time prove more economical in operation.

According, therefore, to the invention, an elastic member is interposed between the nozzle and the sound-generating portion or diaphragm, this intermediate member being acted upon substantially under the influence of the diaphragm. The intermediate member may be provided at the edge of the nozzle itself, or between the part connecting the casing and the nozzle. It is in this connection quite immaterial whether the "nozzle" consists of the ordinary open pipe or tube as well known per se, or whether the same constitutes a nozzle proper of special construction.

By the construction referred to it is accomplished in face of the hitherto known apparatus that due to a good nozzle closure the sound transmitting apparatus according to the invention possesses a greater degree of efficiency, resulting in more economical operation.

In place of diaphragms it is of course also possible to employ tongues, reeds or other mechanical vibratory structures.

The invention will now be described more fully with reference to the accompanying drawing, in which

Fig. 1 shows one specific form of embodiment in section,

Figs. 2-6 being modifications.

Referring to the drawing, in which the same reference characters have been employed throughout for denoting the same parts, *a* represents the sound-generating diaphragm, the operating agent being admitted through *b*. *c* is the elastic intermediate member, which may consist of rubber, leather or a

similar elastic material, or may comprise metallic springs, rings, diaphragms or similar elastic structures.

Whereas in Figs. 1 and 2 the diaphragm is of the usual type, the same in the case of the embodiments according to Figs. 3-6 possesses a central disc or plate, as described in my co-pending application Serial No. 286,315, filed June 18, 1928. In each embodiment, however, the intermediate portion *c*, whether the same be extended as in Figs. 1 and 2 or flat or of annular form respectively as in Figs. 2-6, enables due to its elastic nature the diaphragm or central plate thereon respectively to completely close off the escape of the operating agent upon the return movement of the diaphragm.

In the embodiment according to Fig. 4, for example, the dimensions of the intermediate annular member *c* require to be such that the pressure acting on the surface is less than that acting on the central plate *d*, as otherwise, were the vibratory movement of the diaphragm *c* greater than that of the diaphragm proper *a*, the latter would not vibrate of its own accord.

It is of course understood that I do not restrict myself to the exact forms of embodiment shown, but that various modifications may be made without departing from the spirit of the invention.

What I claim as new and desire to secure by Letters Patent is:

1. In a sound transmitting apparatus employing a fluid operating agent, a diaphragm for generating the sound, a pipe for introduction of the said operating agent, and an elastic member interposed between the said diaphragm and said pipe.

2. In a sound transmitting apparatus employing a fluid operating agent, a diaphragm for generating the sound, a pipe for introduction of the said operating agent, a central plate mounted on the said diaphragm, and an elastic member interposed between the said diaphragm and the said plate.

3. In a form of embodiment of a sound transmitting apparatus employing a fluid operating agent, a diaphragm for generating the sound, a pipe for introduction of the said

100

operating agent, and an elastic member interposed between the said diaphragm and said pipe, the said intermediate member being so chosen in relation to the said diaphragm that the pressure of the operating agent acting on the said intermediate member is less than that acting on the said diaphragm.

5 In testimony whereof I have affixed my signature.
